UNITED STATES PATENT OFFICE.

LLOYD GROFF COPEMAN, OF BELDING, MICHIGAN, ASSIGNOR TO EDWIN W. ATWOOD,
OF FLINT, MICHIGAN.

REFRIGERATING APPARATUS.

Application filed January 14, 1922. Serial No. 529,114.

To all whom it may concern:

Be it known that I, LLOYD G. COPEMAN, a citizen of the United States, residing at Belding, in the county of Ionia and State 5 of Michigan, have invented certain new and useful Improvements in Refrigerating Apparatus, of which the following is a specification.

This invention relates to refrigerating apparatus, and has for its object a refrigerator which is cooled by the circulation of cold water in coils. I have found objectionable sweating in actual practice with a refrigerator in which the coils are evenly distributed 10 throughout the walls. The moisture in the air usually condenses on the top wall of the refrigerator. I have found that the circulation in such a refrigerator is poor.

It is the object of the present invention to 20 provide a condensing chamber which has the function of both promoting circulation and at the same time condensing all the moisture in the air and leading away the water so that the same will not in any way interfere with 25 the food or preserving chamber. This produces an absolutely dry food chamber.

In the drawings,—

Fig. 1 is a diagrammatic view of the refrigerating apparatus.

Fig. 2 is a vertical cross section of the refrigerator taken from side to side.

Fig. 3 is a vertical cross section taken from front to back.

Fig. 4 is a horizontal cross section taken 35 on the line 4—4 of Fig. 3.

Fig. 5 is a plan view (partly broken away) of the condenser chamber.

Fig. 6 is an enlarged section taken on the line 6—6 of Fig. 5.

Fig. 7 is a vertical section through the thermostat taken on the line 7—7 of Fig. 6.

a designates a refrigerator box which is built in the usual way of suitable wood and heat-insulating material. Water enters this refrigerator box through the main *b* from the pressure-controlled pump *c*. This pump is driven by an electric motor *M*. This motor is controlled by a pressure switch *d*, that is, when the pressure in the line rises above, say, 70 pounds, this switch automatically cuts out the current. This is fully described 50 in my prior application #438,593.

The storage tank *e* is provided with an air head which is compressed by the water and 55 which permits the accumulation of pressure

in the water main. The water main *b* leads up through the vertical pipe *f* to the top of the refrigerator box and into a special *T* *h* (see Fig. 6).

The thermostat *i* is slipped into the thermostat socket *j*. This thermostat comprises a coil *k* of two metals of unequal expansion. Consequently these coil up tighter or uncoil due to small variations in temperature, thereby turning the shaft *m* shown in Figs. 60 6 and 7. To the end of this shaft is fastened an electric switch arm *n* which contacts either with the terminal *o* or the terminal *p*. These terminals are connected with circuits which lead to the motor *M'*. This motor is 65 calculated to turn the valve lever *p'* through a quarter of a turn to open and close the valve *q*. This motor apparatus is described in detail in my prior application No. 438,593. Suffice it to say here that it is 70 simply an electric motor with suitable reducing gear and suitable automatic cut-off so that when the valve lever *p'* has been thrown through quarter of a turn the motor automatically cuts off the power. The valve *q* 75 is located in the waste line *r*. This waste line leads from the bottom header *s* which is made up of a plurality of pipe sections and *T*'s.

Likewise the top header is made up of a 80 plurality of pipe sections and *T*'s, as is plainly shown in Figs. 3 and 6. I find it a cheaper construction to use ordinary pipe sections to form the top and bottom headers rather than such a special casting as is 85 shown in my prior application #477,906. It will be noted that the top header *t* is provided with a *T* at the rear (Fig. 5). From this leads two branch pipes *u* which are provided with suitable elbows to afford for 90 each a down run of pipe *v* (Fig. 2). At the bottom of each of these down runs of pipe *v* is a *T* *z*. Out of one end of the *T* a coil *y* runs down the back of the refrigerator. To the other end of the *T* the side coil *z* is connected. This side coil runs down the side of the refrigerator and across the bottom, where it is designated *z'*. Now referring to the other side of Fig. 4, it will be seen that the bottom coil *z'* connects with the bottom 100 header *s* through the *T* 1. The back coil *y* also connects with the bottom header through this same *T*.

The partition coil takes its water from the same source that the condenser coil does. In 110

the center of the upper header ⁵ *t* is a *T* 2 connected by a coupling hose 3 with the inlet end of the condenser coil 4. This condenser coil is located in the condenser chamber 5 which is in the top of the refrigerating box. The condenser has a set of, say, twelve runs running across the condenser chamber, then the pipe drops down to the bottom run, as shown in Fig. 2, and twelve more cross ¹⁰ runs are provided. The condenser pipe is then provided with a run of pipe 6 between the two cross runs of pipe which lead to the elbow 7, where a hose coupling 8 connects with a down pipe 9 (behind the lining of the condenser chamber) which connects with the partition coil 10.

The side walls, the back and partition wall coils are all encased in stonework 11 ²⁰ coated with enamel 100, which stonework is described and claimed in my application No. 477,906. However, there are no coils in the top wall of the food chamber as in the application mentioned, and there is no condenser in application No. 477,906. The condenser chamber 5 is reached through the cover 12. The condenser chamber is connected with the left hand food chamber by the flue 13 which discharges into a larger flue or baffle box 14 located in ³⁰ the condenser chamber. This discharges the warm air above the condenser coils. The air passes over the condenser coils to the opposite side of the condenser chamber where it drops down through the down flue 15 which is provided with a screen 16. The cold air now drops down into the right hand food chamber and passes through the partition opening 17 to the left hand food chamber, forming a continuous circulation. The exposed condenser coils disturb ⁴⁰ the equilibrium of temperature. In short, by reason of the coils in the condenser chamber being exposed, the air in the condenser chamber comes directly in contact with the cold metal and is chilled more than the air that is in contact with the stonework of the food chambers. Consequently the air in the condenser chamber is chilled to a lower temperature and thereby falls and starts a circulation which is necessary to get the best ⁵⁰ results in food preservation.

A very important feature of this condensing chamber is the practical elimination of all sweating in the food chamber. The moisture in the air does not collect on the under side of the top wall of the food chamber as it would otherwise do. The moist air passes up through the up-going flue 18 and is chilled upon the cold coils in the condensing chamber. The moisture there condenses on the coils and falls off into the drip pan 17'. It is carried off through the drain opening 18 and consequently in no way finds its way into the food chamber. ⁶⁰ The tray 17' is spaced from the top wall 19

of the food chamber and is provided with a dead air space. This prevents the top wall of the food chamber from becoming unduly chilled so as to condense the rising moisture.

I have explained in one of my previous ⁷⁰ applications, namely, #440,637, why the thermostat is put directly in the water line instead of in the food chamber. With the thermostat in the food chamber the water will continue to waste at full pressure until ⁷⁵ the food chamber reaches the desired temperature. With the thermostat in the water line, as soon as the water in the coils warms up enough to reach the neighborhood of the thermostat, the thermostat will open the ⁸⁰ waste valve *q* and allow more cold water to take the place of the warm water in the coils. This will not bring the temperature of the food chamber down to the required ⁸⁵ level as quickly, but it obviously will result in a great saving of water for this periodical filling up of the coils and dumping of the water as it warms up results in utilizing all of the heat-absorbing capacity of the water. Consequently very much less water ⁹⁰ is required than where the water is continuously wasted until the food chamber falls to the required degree.

It will be noticed that the water passes from the main *b* through the coils of the refrigerator (the upper and the lower header included) and thence through the main ⁹⁵ *b* to the storage tank *e*. From the storage tank *e* the water is distributed to the various taps, such as 21 and 22. Hence whenever water is being drawn for service purposes the water in the coils will be cold due to the new running water and consequently the thermostat will close the waste. However, in order to provide a much quicker closing ¹⁰⁰ I have provided the waste line with a pressure-controlled check valve 23. This valve will not open unless the pressure in the line is 15 or more pounds and consequently when the service line is open the pressure in the waste line is immediately relieved and the waste line closed. Hence while service water is being drawn the flow of the service ¹¹⁰ taps cannot be diminished by the coincident operation of the waste line.

When the box is of considerable height or capacity, I find it advisable to use two cycles of air circulation and condensation. Instead of a passage-way between the right and left preserving chambers, these are each ¹¹⁵ wholly independent of the other. Each chamber has an up-going flue into the condenser chamber and a down-going flue from the condenser chamber. Preferably two condensing coils are used but this is not absolutely necessary.

What I claim is:

1. In refrigerating apparatus, the combination of a box provided with a preserving chamber and a condensing chamber, and ¹²⁰ ¹²⁵ ¹³⁰

- 5 a water line running in proximity to but in communication therewith to provide an
6 avoiding substantial exposure on the interior air circulation, a water line encased in stone- 60
7 of said preserving chamber and serving to work surrounding the preserving chamber,
8 cool the same and an exposed water line run- a water line running through the condens-
9 ning through the condensing chamber and ing chamber where the same is exposed, and
10 serving to condense the moisture in the air. means in the condensing chamber for in-
11 2. In refrigerating apparatus, the combi- sulating the chilled exposed water line from 65
12 nation of a refrigerator box provided with a the top wall of the food chamber.
13 preserving chamber and a condensing cham-
14 ber connected so as to provide a cycle for
15 air circulation, a concealed water line run- 70
16 ning into proximity to the preserving cham- in communication therewith to provide air
17 ber to chill the same and an exposed water circulation, a water line encased in stone-
18 line running through the condensing cham- work surrounding the preserving chamber, a
19 ber and chilling the same to a lower degree water line passing through the condensing
20 for the purpose of promoting circulation and chamber where the same is exposed, and a 75
21 condensing moisture in the air. tray for carrying away the water of condens-
22 3. A refrigerating apparatus, having in ation and located under the water line in
23 combination, a refrigerator box provided the condensing chamber and insulated from
24 with a preserving chamber and a condens- the top wall of the preserving chamber.
25 ing chamber above the preserving chamber 80
26 and connected therewith to provide air cir-
27 culation through the preserving chamber
28 and the condensing chamber, a substantially
29 concealed water line leading around the pre- 85
30 serving chamber and an exposed water line
31 leading through the condensing chamber.
32 4. A refrigerating apparatus, having in
33 combination, a refrigerator box provided
34 with a preserving chamber, a condensing
35 chamber above the preserving chamber, an
36 up-going flue connecting the preserving
37 chamber with the condensing chamber, and
38 a down-going flue connecting the condens- 90
39 ing chamber with the preserving chamber,
40 a substantially concealed water line lead-
41 ing around the preserving chamber, an ex-
42 posed water line leading through the con-
43 densing chamber so as to chill the condens-
44 ing chamber to a lower degree than the pre-
45 serving chamber and thereby promote a cir-
46 culation of air up through the up-going flue
47 and down through the down-going flue and
48 also condense the moisture in the air.
49 5. A refrigerating apparatus, having in
50 combination a refrigerator box provided
51 with a preserving chamber and with a con-
52 densing chamber above the preserving cham-
53 ber and in communication therewith to pro-
54 vide an air circulation, a water line encased
55 in stone in proximity with the preserving
56 chamber for chilling the same, and a water
57 line running through the condensing cham- 95
58 ber with the coils exposed.
59 6. A refrigerating apparatus, having in
60 combination, a refrigerating box provided
61 with a preserving chamber and a condensing
62 chamber above the preserving chamber and 100
63
- 64 in communication therewith to provide an
65 air circulation, a water line encased in stone- 105
66 work surrounding the preserving chamber,
67 a water line running through the condens-
68 ing chamber where the same is exposed, and
69 means in the condensing chamber for in-
70 sulating the chilled exposed water line from 110
71 the top wall of the food chamber.
72 7. A refrigerating apparatus, having in
73 combination, a refrigerating box provided
74 with a preserving chamber and a condens-
75 ing chamber above the preserving chamber 75
76 in communication therewith to provide air
77 circulation, a water line encased in stone-
78 work surrounding the preserving chamber, a
79 water line passing through the condensing
80 chamber where the same is exposed, and a 85
81 tray for carrying away the water of condens-
82 ation and located under the water line in
83 the condensing chamber and insulated from
84 the top wall of the preserving chamber.
85 8. In refrigerating apparatus, the combi- 80
86 nation of a refrigerating box, a water line
87 running through the refrigerating box to
88 cool the same and continuing on to form
89 a service line, a waste line branching off from
90 said water line and automatically controlled,
91 and a pressure-controlled valve in said waste
92 line which will only open when pressure ac-
93 cumulates in the water line by reason of the
94 service line openings being closed.
95 9. In refrigerating apparatus, the combi- 90
96 nation of a refrigerating box, a water line
97 leading through the box and continuing to
98 form a service line with service taps, a waste
99 line provided with a waste valve thermostati- 95
100 cally controlled, and a pressure-operated
101 check valve in the waste line which prevents
102 water discharging through the waste line
103 although the thermostatically-controlled
104 valve is open, when water is being used out
105 of the service line.
106 10. In a refrigerating apparatus, the com- 105
107 bination of a refrigerator box provided with
108 a dry chamber for preserving purposes and a
109 condensing chamber connected so as to pro-
110 vide a cycle for air circulation, a water line 110
111 imbedded in the walls of said preserving
112 chamber for cooling the same, and an ex-
113 posed water line in said condensing chamber,
114 whereby a lower temperature is obtained
115 in the condensing chamber than is obtained
116 in the preserving chamber to confine the
117 condensation of the moisture in the air to
118 said condensing chamber.
119 In testimony whereof I affix my signature.

LLOYD GROFF COPEMAN.
